(57) **CLAIM**

The ornamental design for a food package, as shown and described.

DESCRIPTION

FIG. 1 is a perspective view of a food package showing my new design;

FIG. 2 is a front side elevational view thereof;

FIG. 3 is a rear side elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an exploded perspective view of the food package shown in FIG. 1.

The broken lines shown in FIG. 8 represent portions of the food package that form no part of the claimed design.

1 Claim, 5 Drawing Sheets
